United States Patent Office.

ENOCH R. MORRISON, OF PITTSBURG, PENNSYLVANIA.

Letters Patent No. 78,117, dated May 19, 1868.

IMPROVEMENT IN MACHINES FOR CASING TOBACCO.

The Schedule referred to in these Letters Patent and making part of the same.

TO ALL WHOM IT MAY CONCERN:

Be it known that I, ENOCH R. MORRISON, of Pittsburg, in the county of Allegheny, and State of Pennsylvania, have invented a certain new and useful Method for Casing Tobacco, or covering the leaves with the sweetening-substance; and the following is a full, clear, and exact description of the same, reference being had to the accompanying drawings, making a part of this specification, in which—

Figure 1 represents a perspective view of one form of machine which I use for this purpose; and it consists of a frame in which is hung a large hollow cylinder, in which the leaves of tobacco and the sweetening-compound are put for coating, and the trough or platform for receiving the tobacco after the process of casing has been performed.

Figure 2 shows a section of the frame through the revolving cylinder, showing the action of the leaves in the cylinder while they are undergoing the process of casing or sweetening.

The object of my invention is to so conduct the manipulations as to save room, time, labor, material, and expense in the process of sweetening, or what is termed by manufacturers "casing tobacco," and making a much better article than is done by the old process of sprinkling and manipulating in vats.

For this purpose I construct a large cylindrical receiver, with an opening, and a close-fitting lid in the periphery, to be taken out for putting in the tobacco-leaves and the sweetening-compound, the same being hung on journals and supported in a frame, which is provided with a vat or casing-platform underneath, to receive the contents on after the process of the mixing and casing is completed.

To enable others to make and use my invention, I will describe it more in detail, referring to the drawings, and to the letters of reference marked thereon.

I make a frame, A, of any suitable or desired dimensions, of posts A A A A, connected together with horizontal side-timbers B B, and cross-ties C C, the lower portion of the frame being plank, forming a tight floor, platform, or vat, D, which is elevated to a convenient height for working at easily to remove the tobacco after it is emptied upon it.

On the two-top side-timbers B B are secured journal-boxes b b, in which is hung the revolving cylindrical receiver E, which may be made of any desired dimensions, both in width and diameter. It may be made with four, six, eight, twelve, or more sides, or round, as shown in the drawings.

The cylindrical form is as good as any other, and as cheaply made. The inside surface being smooth, may be provided with a sufficient number of ribs, or half-round projections, e e e e, to prevent the leaves of tobacco from sliding in a mass on the lower portion of the cylinder as it is being slowly revolved to case over and moisten the leaves with the sweetening-substance, which is usually composed of sugar, or honey and licorice, in such proportions as the different grades of tobacco require.

The receiver E may be put in motion and operated by having a pulley, F, on one end of the shaft which it hangs on, and a band, f, or belt to connect it with a counter-pulley, G, to be turned by a crank-handle, or by any convenient motive-power.

The "modus operandi" of casing tobacco by my method, as above described, is very easily understood, and may be done by boys, or any ordinary hands, not requiring skill, as is the case by the old process. It is simply to remove the cover I from the receiver E, put in a given quantity of tobacco-leaves, and also a given quantity of the liquid compound, close up the receiver, and rotate it for a short time, and every portion of the contents will become thoroughly coated in a perfectly uniform manner, when the lid I is taken out and the cylinder turned so as to empty the contents on to the vat or platform D, from whence it can be taken at pleasure, packed, and disposed of. After the cylinder E is emptied, another batch can be put in immediately, and the lid put in place and secured, so that no time need be lost in clearing the vat D, as the process of casing does not in the least interfere with the removing of that which is done.

In order to contrast the difference between my method of "casing tobacco" and the old and only mode in practice heretofore of manipulating it for the purpose, I will briefly describe the common practice, which is to

build a casing-platform or vat, commonly spreading over quite a large space, and is usually lined with zinc. A single layer of the tobacco-leaves is spread over the platform. The sweetening-substance being prepared, it is then sprinkled upon the leaves with a broom, which process requires much practice and skill to distribute the compound evenly, so as to make it all alike, as a given weight of tobacco requires a given quantity of the compound; and if the leaves are not all wet, or saturated, the tobacco will not be of the same flavor, and if more of the sweetening-substance is put on than is absorbed by the leaves, it is lost. By this course of procedure, it is necessary that the tobacco should lie till the leaves have taken up all they can, and the dry spots become moist, and to facilitate this part of the process, it often becomes necessary to fork up and manipulate the mass in the vat or on the casing-platform, so that there may be a greater uniformity in the taste of the different grades of tobacco—a matter of great importance to manufacturers, so much so that men qualify themselves and become experts at sprinkling tobacco.

The advantages of my simple, cheap, and efficient method, as above described, over the old one of manipulation, may be summed up as follows, viz:

My method, when carried out, does not cost more than one-half as much as the old casing method by the use of the vat. It does not occupy or require more than one-fourth of the space or room to work it. Any ordinary man, or boy of twelve or fourteen years of age (without regard to race or color) can work it. More than five times the quantity of tobacco can be prepared and cased in a day, and every batch made perfectly uniform in taste and quality, and at least ten per cent. of the sweetening-substance saved which is wasted by the old method. The sweetening-compound being prepared and put into the receiver hot, it almost instantly saturates the whole mass.

The sweetening-compound is usually composed of sugar and licorice, of about equal parts, from two to four pounds to the gallon of the liquid. Honey may be used in the place of the sugar, if desired.

Fifty pounds of leaf-tobacco will absorb about four gallons of the compound, which is of about the same consistence as honey or thin molasses, which, by my new method of manipulating, is all taken up and absorbed within two minutes from the time it is put in with the tobacco and the receiver put in motion.

What I claim as my invention, and desire to secure by Letters Patent, is—

The method of casing tobacco, by means of a hollow revolving vessel, receiver, or its equivalent, working on a shaft, journals, or rollers, the receiver being made of any required shape or dimensions, for the purposes set forth.

E. R. MORRISON.
